CLEANSING APPARATUS

Rex H. Sanford, Duluth, Minn.

Application November 20, 1940, Serial No. 366,339

11 Claims. (Cl. 141—9)

This invention relates to cleansing apparatus and more particularly to apparatus adapted for cleansing dishes, table flat ware, cooking utensils and the like, which are hereinafter generically referred to as dishes, and among the important objects of the present invention is to provide a novel apparatus of the aforesaid character of simple and economical construction and efficient and positive operation.

Yet another object of the present invention is to arrange dishes to be cleansed in a container associated with a cleansing solution and to forcibly discharge the cleansing solution onto and over dishes in a novel manner so as to thereby effect efficient and thorough cleansing of the dishes.

Other objects are to forcibly impel a cleansing solution onto and over dishes from a plurality of directions and thereby insure efficient cleansing of all portions of the dishes; to so arrange the solution impelling means that synchronic operation thereof may be effected and thereby insure an efficient cleansing action; to enable dishes to be effectually washed with a minimum of cleansing solution; to employ novel solution impelling means; and to so arrange the impelling means and the power supply therefor that the same may be disposed within the container for the cleansing solution and the dishes to be cleansed.

Other and further objects of the present invention will be apparent from the following description and claims and are illustrated in the accompanying drawings which, by way of illustration, show preferred embodiments and the principle thereof and what I now consider to be the best mode in which I have contemplated applying this principle. Other embodiments of the invention embodying the same or an equivalent principle may be used and structural changes may be made as desired by those skilled in the art without departing from the present invention and the purview of the appended claims.

In the drawings,

Fig. 1 is a perspective view of the container or rack in which dishes to be cleansed in my novel apparatus may be arranged and showing the manner in which the cleansing solution impelling means is associated with such rack;

Fig. 2 is a longitudinal sectional view through an apparatus embodying my invention;

Fig. 3 is a transverse sectional view taken substantially on the line 3—3 on Fig. 2;

Fig. 4 is a perspective detail view of the impeller arrangement employed in the form of the invention shown in Figs. 1 to 3;

Fig. 5 is a horizontal sectional detail view taken substantially on the line 5—5 on Fig. 6 and showing another form of my invention;

Fig. 6 is a transverse sectional detail view taken substantially on the line 6—6 on Fig. 5; and

Fig. 7 is a perspective detail view of one of the impellers employed in the form of the invention illustrated in Figs. 5 and 6 and showing the drive for this impeller as well as the drive for other similar impellers included in the apparatus.

The form of the invention shown in Figs. 1 to 4 includes a housing 8 preferably in the form of a substantially rectangular open top tank. A cover or lid 9 is provided for the housing and includes an inwardly offset flange 10 at the lower edge thereof defining a shoulder 11 adapted to rest on the upper free edge of the housing or tank 8 when the flange 10 is passed into the upper part of the tank whereby a tight closer is provided for the open top of the tank. A false or extra bottom 12 provided in the tank is supported in spaced relation with the bottom and side walls of the tank by inclined plates as 13 which extend between the corners at the bottom of the walls of the tank and the bottom thereof whereby a trough T, described in further detail hereinafter, is provided.

An open mesh wire basket 14 is removably rested on the upper surface of the false bottom 12 and has suitably formed supports as 15 on the bottom thereof on which dishes to be cleansed may be rested to be supported in position to be cleansed. In the case of flat pieces, such as plates and saucers, these are arranged in association with the supports 15 in vertical position, as shown in Fig. 1, whereas bowls, cups and the like are preferably arranged in inverted position as shown in Fig. 1. I have found it convenient to include in the basket 14 a wire mesh tray or like container 16 in which table flat ware, such as knives, forks and spoons and the like may be disposed for cleansing, and preferably the mesh of this tray or basket 16 has smaller openings than those of the main basket 14 so as to insure retention of such articles in the tray 16.

In use, the tray or basket 14 is rested on the false bottom 12 to have a cleansing solution contained in the tank 8 above the inclined walls as 13 thrown onto dishes in the basket 14, suitable impelling means being provided for this purpose. Thus, stud shafts as 17 are journaled in bearings as 18 mounted on the inclined walls 13 at each of the four corners of the false bottom 12 so as to thereby be disposed at the four corners of the

basket 14 when it is arranged on the bottom 12. Grooved pulleys as 19 are, in the present instance, fast on the stud shafts 17 and an endless V-belt 20 is mounted in the grooves in the pulleys 19 to thereby pass around the basket 14 when it is arranged on the bottom 12, but it is to be understood that sprockets and chains or equivalent means could be used in place of the pulleys 19 and belt 20. One of the aforesaid shafts is the shaft 17a of an electric motor 21 carried by a bracket 22 fast to an adjacent wall of the tank 8. When the motor 21 is set in operation, the shaft 17a drives the pulley 19 fast thereon and in this way the belt 20 is caused to travel about the pulleys 19 and therefore the basket 14.

At spaced intervals along the outwardly disposed edge of the belt 20 recesses as 22 are formed preferably by providing a slot in the outer marginal portion of the belt 20 and by cutting away a portion of the margin of the belt as at 23 inwardly from each end of the aforesaid slot or recess. Impellers as 24 are mounted in the recesses 23 and consist of relatively flat body portions which are disposed in the recesses 22 and which are fast to the belt 20 as by rivets 25 or the like. The impellers 24 have inclined deflector vanes as 26 at opposite ends thereof for the purpose of impelling the cleansing solution onto dishes in the basket 14. The trough T and the pulleys 19 are so disposed relative to each other and the impellers 24 are so constituted and arranged and are so located on the belt 20 that the lower portions of the impellers are immersed in the cleansing solution introduced into the trough T so as to substantially fill the same, the configuration of the trough being such that it may be filled with but a relatively small quantity of cleansing solution whereby only a minimum quantity of such a solution is required in the apparatus.

Hence, after the basket 14 has been arranged on the bottom 12 and sufficient cleansing solution has been introduced in the trough T to cause approximately one-half of the impellers 24 to be immersed in such solution and the lid 9 has been arranged in tank-closing position, the motor 21 is set in operation. Then by reason of the fact that the impellers 24 are arranged at the outer edge of the belt 20 and since these impellers extend into the cleansing solution in the tank, the impellers are effective in the course of movement of the belt 20 to throw the cleansing solution, which may be suitably saponified water or the like, up onto dishes in the basket 14 and tray 16. Since the belt 20 passes about all four sides of the basket 14 and since the impellers are arranged at such spaced intervals in the belt that at least one impeller will at all times be disposed on each side of the basket 14, the cleansing solution is thrown onto the dishes from a multiplicity of angles and, in fact, from substantially all directions, and in this way the cleansing solution is caused to be forcibly impelled on all portions of the dishes arranged in the basket 14 and in this way effective cleansing of all portions of the dishes is effected. By reason of the configuration of the trough T and the interrelation between this trough and the impellers 24, it is only necessary that a comparatively small amount of a cleansing solution be introduced into the trough T and this is augmented by the fact that the solution quickly drains back into the trough after being impelled onto the dishes in the basket 14. It will also be understood that the deflector vanes 26 on the impellers 24 are con-

stituted and arranged in such a way as to insure effective and forceful discharge of the cleansing solution directly from the trough onto the dishes. The function of the lower vanes 26 of the impellers 24 is to scoop up the cleansing solution and throw it upwardly to splash against the dishes, while the upper vanes 26 aid to impart further momentum to the solution and to direct it over and onto the dishes.

10 Another form of my invention is shown in Figs. 5 and 6 and here again a tank, that is preferably substantially rectangular in outline, is provided and this tank 27 has the open top thereof closed by a lid 28 similar to the lid 9. In this instance 15 brackets 29 are mounted at suitably spaced positions on the inner sides of the vertical walls of the tank 27 and have hook-shaped portions at the free ends thereof in which the upper marginal rim of a basket 30, similar to the basket 14, may be suspended to thereby support the basket 14 in the tank 27. It will be understood that, 20 if desired, brackets corresponding to the brackets 29 might be provided in the tank 8 to support the basket 14 therein. Resort, however, is had to the brackets 29 in the form of the invention shown in Figs. 5 and 6 for in this form of the invention a rounded false bottom 31 is rested on the bottom of the tank 27 to have the high point thereof arranged substantially medially of the 25 tank 27 and with the marginal edges thereof terminated inwardly of the vertical walls of the tank 27 to thereby define a trough Ta similar to the trough T.

30 Adjacent each of the corners of the tank 27 and at suitable intervals intermediate such corners bearings as 32 are provided on the bottom of the tank 27 in the trough Ta and brackets 33, providing bearings 34, are fast to the upright walls of the tank in such a way as to have the bearings 34 aligned with the bearings 32. 35 Stud shafts as 35 are journaled in each of the sets of aligned bearings 32 and 34 and have at the upper ends thereof grooved pulleys as 36 in which an endless belt 37 is arranged. One of the shafts 35 is afforded by the shaft 35a of a motor 36 carried by a bracket 33 secured to the adjacent wall of the tank 27, this shaft 35a being journaled in a bearing 34 of one of the brackets 33 supported by the wall of the tank.

40 35 A hub as 38 is fast on each shaft 35 and on the shaft 35a immediately above the bearing 32 and has a suitably formed impeller blade 39 thereon. Each hub 38 and its impeller blade 39 is disposed vertically on the shaft 35 (or 35a) to 45 be in communication with a cleansing solution stored in the trough Ta, each impeller blade 39 being constituted and arranged, when the shaft on which it is mounted is set in operation, to throw the cleansing solution from the trough Ta over and onto dishes in the basket 30, the solution so thrown over and onto the dishes effecting cleansing thereof and draining back into the trough Ta to permit re-use thereof.

50 As in the case of the tank 8, a cleansing solution is provided in the tank 27 so as to partly 55 immerse the impeller blades as 39. As best shown in Fig. 5, in addition to the impeller blades at the corner of the tank 27, preferably two impeller blades are provided along the longer side of the tank 27 intermediate the corners, and preferably in uniformly spaced relation, and another impeller blade is provided along the shorter walls of the tank, preferably in uniformly spaced relation with the impeller blades at the 60 corners. Hence when the motor 36 is set in

75

operation and the belt 37 is caused to travel about the pulleys 36, the shafts 35a and 35 are rotated and thereupon the impeller blades 39 throw the cleansing solution onto dishes in the rack 30. By reason of the aforesaid distribution of the impeller blades 39 on all sides of the rack 30, the cleansing solution is thrown onto the dishes in the rack from all sides whereby an effective cleansing action results.

While resort may be had to a number of ways of draining the cleansing solution from the tanks 8 and 27, a suitable drain cock as 40, Fig. 2, may be provided which, when opened, will permit the cleansing solution to drain from the tank, and if resort is had to such an arrangement the trough as T or T_a in each tank will be arranged to be inclined toward the drain cock so as to insure drainage of the cleansing solution from the trough when the cock is opened.

It will be manifest from the foregoing description that I have provided a simple and relatively inexpensive cleansing apparatus particularly adapted for the cleansing of dishes as this term is used generically therein. Such an efficient cleansing action arises by reason of the fact that a cleansing solution may be impelled or thrown onto dishes arranged in the apparatus from a wide variety of positions and, in effect, from all directions so that cleansing solution is impelled onto all portions of the dishes arranged in the apparatus. Moreover, the arrangement is such that efficient cleansing may be effected with a minimum quantity of cleansing solution.

Thus while I have illustrated and described selected embodiments of my invention, it is to be understood that these are capable of variation and modification and I therefore do not wish to be limited to the precise details set forth but desire to avail myself of such changes and alterations as fall within the purview of the following claims.

I claim:

1. In an apparatus of the class described, a container in which dishes and the like to be cleansed may be arranged and into and from which a cleansing solution may freely pass, a cleansing solution receiver disposed about said container and into which a cleansing solution may be introduced, a plurality of impeller members disposed about said container and including parts adapted to extend into a solution introduced into said receiver, said impeller members being so disposed and being so operative as to forcibly eject solution from said receiver over and onto dishes or the like in said container from a plurality of positions, and means interconnecting said impeller members to effect conjoint operation of said impeller members and including a flexible member interconnecting said impeller members, said flexible member being disposed in a generally horizontal plane within said receiver and above the solution therein.

2. In an apparatus of the class described, means into which a cleansing solution may be introduced about an area in which dishes or the like to be cleansed may be arranged, an endless flexible member passed about said area and having impeller means arranged at spaced intervals thereon operative to pick up solution from the first-named means and discharge it onto dishes or the like in said area, and means for driving said endless member about said area to thereby cause said impeller means to discharge the solution onto the dishes or the like from a plurality of positions.

3. In an apparatus of the class described, means into which a cleansing solution may be introduced about an area in which dishes or the like to be cleansed may be arranged, a plurality of impeller members arranged in spaced relation with each other about said area and including parts adapted to extend into a cleansing solution introduced into said first-named means to substantially fill the same and operative to pick up solution from the first-named means and discharge it onto dishes or the like in said area, means operatively connected to said impeller members to produce conjoint operation of said impeller members and including an endless flexible member interconnecting said impeller members, said endless flexible member being disposed in a generally horizontal plane within said first-named means and above the solution-containing area of said first-named means, and means for driving said flexible member to operate said impeller members and thereby cause the same to discharge the solution onto the dishes or the like from a plurality of positions.

4. In an apparatus of the class described, a container in which dishes and the like to be cleansed may be arranged and into and from which a cleansing solution may freely pass, means providing a trough-like portion about said container and into which a cleansing solution may be introduced, an endless flexible member, means supporting said endless member and arranged to direct the same about said container, impeller members on said endless member at spaced intervals and operative to discharge solution from said trough-like portion onto and over dishes and the like in said container, and means for causing said endless member to travel about said container.

5. In an apparatus of the class described, a container in which dishes and the like to be cleansed may be arranged and into and from which a cleansing solution may freely pass, means providing a trough-like portion about said container and into which a cleansing solution may be introduced, an endless belt, pulleys mounted at intervals about said container and in which said belt is arranged to be guided about said container, a plurality of impeller members mounted on said belt at spaced intervals and including deflector vanes operative to discharge solution from said trough-like portion onto and over dishes and the like in said container, and means for causing said belt to travel about said container.

6. In an apparatus of the class described, a container in which dishes and the like to be cleansed may be arranged and into and from which a cleansing solution may freely pass, means providing a trough-like portion about said container and into which a cleansing solution may be introduced, a plurality of impeller members mounted at spaced intervals about said container and operative to discharge solution from said trough-like portion onto and over dishes and the like in said container, and means interconnecting said impeller members and disposed within said trough-like portion and above the solution-containing area thereof and including a flexible member disposed in a substantially horizontal plane and interconnecting said impeller members, and means for driving said flexible member to thereby operate said impeller members.

7. In an apparatus of the class described, tank-like means providing an enclosure and arranged to provide a trough-like portion about the medial

part of the enclosure and into which trough-like portion a cleansing solution may be introduced, a container disposed at the medial part of said enclosure in which dishes and the like to be cleansed may be arranged and into and from which a cleansing solution may freely pass, a plurality of impeller members disposed about said container and including parts adapted to extend into a solution introduced into said trough-like portion, said impeller members being so disposed and being so operative as to forcibly eject solution from said trough-like portion over and onto dishes or the like in said container from a plurality of positions, and means operatively associated with said impeller members for conjointly operating said impeller members and including a flexible member interconnecting said impeller members, said flexible member being disposed in a generally horizontal plane within said enclosure and above and relatively close to the solution contained in said trough-like portion.

8. In an apparatus of the class described, tank-like means providing an enclosure and arranged to provide a trough-like portion about the medial part of the enclosure and into which trough-like portion a cleansing solution may be introduced, a container disposed at the medial part of said enclosure in which dishes and the like to be cleansed may be arranged and into and from which a cleansing solution may freely pass, an endless flexible member passed about said container and having impeller means arranged at spaced intervals thereon operative to pick up solution introduced into said trough-like portion to substantially fill the same and to discharge the solution over and onto dishes and the like in said container from a plurality of positions, and means for causing said endless member to pass about said container.

9. In an apparatus of the class described, tank-like means providing an enclosure and arranged to provide a trough-like portion about the medial part of the enclosure and into which trough-like portion a cleansing solution may be introduced, a container disposed at the medial part of said enclosure in which dishes and the like to be cleansed may be arranged and into and from which a cleansing solution may freely pass, an endless belt, pulleys mounted at intervals about said container and in which said belt is arranged to be guided about said container, a plurality of impeller members mounted on said

5 belt at spaced intervals and including deflector vanes operative to discharge solution from said trough-like portion onto and over dishes and the like in said container, and means for causing said belt to travel about said container.

10. In an apparatus of the character described, a tank-like receptacle, a container disposed within said receptacle for supporting dishes and the like to be cleansed and into and from which a 10 cleansing solution may freely pass, means affording a trough in the bottom of said receptacle around said container and adapted to receive a cleansing solution, a plurality of rotatable impeller members disposed in spaced relation about said container, bearing means secured to said receptacle and supporting said impeller members for rotation about vertical axes, each of said impeller members having a vane disposed within said trough and operating when rotated to discharge solution from said trough onto the dishes 15 and the like in said container, an endless belt extending around said container and frictionally connected to said impeller members for rotatively driving the same, and means for causing said belt to travel around said container.

11. In an apparatus of the character described, a tank-like receptacle, a container disposed within said receptacle for supporting dishes and the like to be cleansed and into and from which a 20 cleansing solution may freely pass, means affording a trough in the bottom of said receptacle about said container and adapted to receive a cleansing solution, a plurality of pulley members rotatably mounted on vertical axes located at spaced points about said trough, an endless 25 flexible member disposed in a generally horizontal plane and operatively engaged with all of said pulleys and supported and guided thereby, a plurality of horizontally spaced impellers located 30 at least in part in the solution in said trough and constructed and arranged to provide impeller surfaces which in horizontal movement of said impellers are operative to discharge solution from said trough onto and over dishes and the like in said container, and means connecting each 35 of said impellers to one of said members to impart such horizontal movement to said impellers when said members are operated, and means for causing operation of said pulley members and 40 said endless flexible member to thereby operate said impellers and discharge solution onto and over dishes and the like in said container.

REX H. SANFORD.
